ELECTRIC CIRCUIT BREAKER WITH SPARK
SEALED CASINGRichard C. Ingwersen, Jackson, Mich., assignor
to Mechanical Products, Inc., Jackson, Mich., a
corporation of Michigan

Application January 19, 1953, Serial No. 331,769

6 Claims. (Cl. 200—114)

1

This invention relates to electric circuit breakers of the kind which comprise a split casing structure enclosing fixed and movable contacts, with the movable contacts being electrically connected with a thermal latch device, which device is operative to release the movable contacts to move rapidly and automatically to open position upon the occurrence of current overload or a short circuit. More particularly, the invention relates to plug type thermal circuit protectors for use in a standard Edison base fuseholder to provide overcurrent and short circuit protection for branch and service circuits and comprising a casing composed of two semi-cylindrical casing sections of insulating material held connected together in cylindrical plug form by separate end-caps mounted over opposite end portions of the assembled casing sections. These assembled casing sections define a hollow space within the casing, in which space the fixed and movable contacts are located, and which space is open at one end of the casing to a central opening formed in the corresponding casing end wall and end cap for the passage of an actuator plunger, which plunger is actuatable to re-set the thermal latch and close the movable contacts against the fixed contacts.

In connection with these electric circuit breakers, it has been necessary, in order to satisfy Underwriters' Laboratories requirements, to devote much attention to the problem of effectively sealing the casing against the egress of the electric arc flame which occurs within the casing upon the controlled circuit being suddenly broken at the fixed and movable contacts and, further, to preventing the gases evolved, upon arcing occurring, from forming an electrical conductive path with respect to the outside of the casing.

It should be pointed out here that the present invention is concerned with a circuit breaker of the above kind in which the fixed and movable contacts are located within a portion of the split casing interior so that the electrical arc is concentrated in such interior casing portion and comes into contact with such portion of the metal contacts and their conductor strips as it is not practically possible to shield from the electrical arc. Further, when arcing occurs, this gives rise to internal pressure which tends to burst open the split casing so that the arc evolved gases tend to flow towards the casing splits and carry with them particles of the contacts and conductors resulting from volatilizing of the metal due to the arc flame. The portion of the casing interior in which this arcing and attendant volatilizing ac-

2

tion occurs is encased by an exteriorly applied metal end cap, which resists actual bursting apart of the casing sections, but which must be protected against the possibility of setting up with the said particle laden gases an electrically conductive path if the circuit breaker is to possess the necessary dielectric strength.

It is an important object of the present invention, therefore, to provide an electric circuit breaker of the above kind which has satisfactory dielectric strength between the interior contacts and the encircling end cap.

It is also an object of the invention to provide an electric circuit breaker of the above kind in which the gases evolved upon the occurrence of arcing are prevented from forming an electrically conductive path between the live contacts and the encircling casing end cap.

It is a further object of the invention to provide an electric circuit breaker of the above kind in which the casing split is effectively sealed against the escape of the arc flame and gases.

The above and further objects and advantages of the invention, residing in the construction, arrangement and combination of parts will become clear from a consideration of the following description of one practical form of the invention, by way of example, with reference to the accompanying drawings, and from the appended claims.

In the drawings:

Fig. 1 is a perspective view of an electric circuit breaker in accordance with the invention, with an end portion of the casing and corresponding end cap broken away to reveal the side split sealing means.

Fig. 2 is an elevational view looking upon the inside of one half of the casing of the circuit breaker according to the invention, with the other casing half removed but showing the thermal latch and actuator plunger in position and, in dotted lines, the position which the end caps and sealing washers occupy in the assembled condition of the parts.

Fig. 3 is a longitudinal section of a circuit breaker and casing assembly according to Fig. 2 but with the parts completely assembled and taken in a plane corresponding to the line *a—a* in Fig. 2, the contacts, thermal latch and plunger parts being shown in elevation,

Fig. 4 is a transverse section on the line *b—b* of Fig. 2,

Figs. 5 and 6 are transverse sections on the lines *c—c* and *d—d*, respectively, of Fig. 2, with the thermal latch and associated parts removed,

Fig. 7 is a detail view, illustrating the sealing washer with diametral side split sealing finger portions.

Fig. 8 is a perspective cut-away view of this circuit breaker, with the contacts closed, and

Fig. 9 is a similar view to Fig. 8 but with the contacts open.

In the drawings, the casing construction is shown composed of two similar semi-cylindrical casing sections 1 and 2 of insulating material, which sections when the casing sections are assembled together define diametrically opposite longitudinally extending splits 3 on the opposite sides of the cylindrical casing, the casing sections being held in assembled relationship by a pair of end caps, indicated generally at 4 and 5.

The casing sections combine to form an enclosed interior chamber indicated generally at 6, in which there are mounted a pair of diametrically spaced fixed contacts 7, and in which chamber there is also mounted a thermal latch and movable contact unit, indicated generally at 8, and an actuator plunger 9.

The unit 8 comprises a thermal latch assembly presenting oppositely disposed substantially U-shaped bimetallic latch parts 10 united by integral bridge portions 11, upon which portions the movable contacts 12 are mounted for engagement with their companion fixed contacts 7. The fixed contacts 7 and movable contacts 12 are located within an end portion 6a of the chamber 6 disposed adjacent the casing end wall 23 having the central opening 22 through which the actuator plunger 9 extends. An opening 4b in the end cap 4 provides for the passage of the plunger with all round clearance, as seen in Figs. 1 and 3.

The unit 8 is slidable relatively to the plunger 9, with the latch parts 10 being located upon opposite sides of the plunger and being adapted to have releasable latching engagement with abutment ledges 13 (Figs. 2, 8 and 9) secured upon the plunger. These ledges are preferably provided by separate metal L-shaped parts secured upon the plunger 9, as by a rivet 14. By providing the abutment ledges 13 upon separate metal parts, instead of directly upon the plunger, undue wear upon the plunger is avoided, it being appreciated that the plunger itself is formed from insulating material.

The unit 8 is held stressed into engagement with the abutment ledges 13 by the action of a pair of coil springs 15 connected between the bridge portions 11 and laterally protruding ears 16 at the inner end of the plunger. These springs are stressed when the unit 8 is moved relatively to the plunger 9 to engage the bimetallic latch parts 10 with their abutment ledges 13 as seen in Figs. 2, 3 and 8. It is to be noted that the parts 18 are electrically conductive. When the contacts 11 and 12 are closed, and the circuit breaker is in circuit, the current flow takes place between the contacts, in series along the limbs of the U-shaped latch parts 10.

The plunger 9 is itself biased by a coil spring 18, which spring is compressed when the latch parts 10 are engaged with their abutment ledges 13, but acts immediately to project the end 19 of the plunger farther out of the corresponding casing end when the latch parts 10 are disengaged from the ledges 13 as seen in Fig. 9. Such disengagement takes place automatically, due to the bimetallic nature of the latch parts 10 and their distortion under the influence of the heat of the conducted current, and will oc-

cur when the current reaches a predetermined value, above that for which the bimetallic parts 10 have been calibrated, which calibration may be, for example, 15, 20, 25 or 30 amperes.

The plunger is provided with a band portion 20, which extends outside the casing when the plunger end 19 is projected, as stated, and by being distinctively colored, for example, serves to give a visible indication that the circuit, controlled by the circuit breaker, has been broken.

Fixedly mounted upon the plunger there is a washer 21, which is formed and arranged to seal against the inside of the central opening 22 in the casing end wall 23 when the circuit is broken so as to seal that opening against the escape therethrough of the arc flame and evolved gases resulting from the circuit being suddenly broken at the contacts 7 and 12 due to the release of the latch parts 10 from their abutment ledges 13 and the action of the springs 15. An additional seal is provided by a washer 24 retained between the casing end wall 23 and the end cap 4. Yet a further seal is provided by a second sealing washer 25 having a disc portion mounted upon the washer 24 and formed with integral diametral finger portions 27 which are deformed to extend along and cover the portions of the longitudinal casing splits 3 which lie within the confines of the side flange 4a of the end cap 4. It is important to note that the flange 4a of the end cap 4 completely embraces that portion of the casing which contains the chamber 6a in which the fixed and movable contacts are located and in which arcing occurs. It is also important to note that the diametral finger portions 27 of the sealing washer 25 extend the entire extent of the inside of the end cap flange 4a and are deformed by this flange into firm and sealing engagement with respect to the portions of the longitudinal casing splits 3 embraced by said cap flange. These finger portions 27 seal the casing slits against the possible egress of gases, resulting from arcing, and thereby prevent these gases, with metal particles carried thereby, from forming an electrically conductive path with the end cap 4.

The sealing washers 24 and 25 could be formed in one, if desired, and are conveniently formed from vulcanized fibre material. When formed in one the disc portion of the washer may be relatively rigid, the finger portions 27, however, being capable of deformation into their required sealing position over the said portions of the casing splits 3 when the end cap 4 is applied, as will be understood.

The end cap 4 is deformed inwardly at its inner end to permanently embrace the casing shoulder 25, as indicated at 26, this shoulder being located on the casing beyond the said chamber portion 6a.

The other end cap 5 is shown formed with a screw threaded skirt portion 27, screwed into position upon the corresponding screw threaded end portion 28 of the combined casing sections, and adapted for screwing into operative position with respect to a socket (not shown) containing the main electric supply terminals of the circuit to which the circuit breaker is required to be applied, and with which supply terminals electrical connection is maintained by a terminal end cap 29.

The casing sections 1 and 2, along their longitudinally opposed edge surfaces, are formed with complementary, elongated recesses 30, which define longitudinally extending channels 31 in which

electrical conductor strips 32 and 33 are accommodated, the conductor 33 being in electrical conducting relationship to the terminal end cap 29, and the other conductor strip 32 being in electrical conducting relationship with respect to the screwed cap portion 27.

These conductor strips are fixed in position within the casing, and carry the fixed contacts 7. As appears clear in Figs. 2, 8 and 9, the channels 31 are of tortuous form, and the conductor strips are correspondingly shaped. As a result, such portion of the evolved arc flame or flash as may seek to escape along these conductor strips within their respective channels will be constrained to follow a correspondingly tortuous path so as thereby to baffle its flow to the outside of the casing.

It is to be noted that the fixed contacts 7 are carried upon end portions 34 of the conductor strips which are bent inwardly in opposite directions into substantially arcuate form, as shown in Figs. 4, 8 and 9 to dispose their fixed contacts 7 in diametrically spaced relationship and as remotely as possible from the casing split 3. It is also to be noted with respect to Figs. 4 and 5, in particular, that the casing interior is formed with inwardly projected wall portions 35 which present wall surfaces 36 in proximity to the curvedly bent portions 37 of the conductor strip portions 34. These casing wall portions 35 and their wall surfaces 36 are of particular importance and serve the purpose of protecting the portions 37 of the conductor strips from the direct effect of the arc which occurs when the circuit is suddenly interrupted at the contacts 7 and 12. In this connection, and as will be appreciated by those skilled in the art, this arc will tend to follow a substantially circular or magnetic loop-like path in which the conductor strip portions 37 are located. However, the wall surfaces 36 are also located in said path, immediately ahead of their respective conductor strip portions 37 and, accordingly, said wall surfaces serve as baffles to prevent the arc flame or flash from striking against the otherwise exposed conductor strip portions and causing erosion thereof. That this is so has been proven in practice, by observing the occurrence of "scorching" upon these wall surfaces upon arcing occurring.

Protection from the direct effect of the arcing is provided with respect to the bimetallic latch portions 10 by fitting the bridge portions 11 with surface plates 38 having side portions 39 which overlie the upper ends of the latch portions 10, as seen in Figs. 4, 8 and 9, in particular, and thus conceal the latch portions from the direct effect of such arcing, which, as concerns these latch portions, must first hit against the surface plates 38.

In operation, with the parts as shown in Figs. 2 and 3, the circuit is closed at the contacts 7 and 12 and current can be conducted from the conductors 32 and 33, through the closed contacts and the series connected U-shaped latch parts 10.

As the latch parts 10 become heated by the conducted current they will distort laterally outwards from their position of contact with their abutment ledges 13 and, in the event the overload current value is reached, will distort to such extent that the latch parts disengage these ledges. When this happens the unit 8 will immediately move downwardly (as seen in Figs. 2 and 3) by the action of the coil springs 15 and cause the circuit to be broken suddenly at the contacts

1 and 12. This movement of the unit 8 will be arrested when the parts 11 come into contact with fixed abutment surfaces 40 formed within the split casing interior. The resulting arc will be dissipated within the casing by the combined action of the seals 21, 24, 25 and 27, the baffle walls 36, the surface plates 38 and tortuous channels 31, preventing bursting of the casing 1, 2 and the possibility of any exterior harmful effect. With the opening of the contacts the plunger 9 will immediately snap outwards by the action of its spring 18 and cause the indicator band 20 to be visibly positioned outside the casing wall 23.

To re-set the circuit breaker it is merely necessary to push the plunger 9 inwards to re-position the abutment ledges 13 with respect to the latch parts 10, it being appreciated that the unit 8 is held positioned for this to take place due to the engagement of parts 11 with the abutment surfaces 40. Release of the plunger then allows the movable contacts 12 to re-engage their fixed contacts 7 with the latch parts also re-positioned for operation to break the circuit upon the re-occurrence of an overload.

The disc portions of the sealing washers 24 and 25, or the single disc portion if the separate washer 24 is dispensed with, are formed with central openings 29 through which the plunger 9 is able to have a sliding fit. These washers, however, extend completely over the diametral splits formed in the casing end wall 23 and thus seal these splits upon the outside of said end wall.

The washer 21, on the plunger 9 is shown in Fig. 4 as being of substantially rectangular shape and as providing surface portions which will completely cover the inner end of the opening 22 provided for the passage of the plunger 9, and presented to the interior of said casing chamber portion 6a. When the plunger is in the set position, with the contacts closed, this washer 21 will be spaced inwardly from the said opening 22. However, it is found in practice that the action of the springs 15 upon disengagement of the thermal latch parts 10 is so rapid that the washer 21 reaches the opening 22 to seal the same at the time when arcing occurs due to breaking of the controlled circuit at the contacts 7 and 12.

Having thus described my invention, what I claim as novel and wish to secure by Letters Patent is as follows:

1. In an electric circuit breaker having a hollow casing formed by separate casing sections held assembled together by exteriorly applied end cap means, and including fixed and movable electrical contacts enclosed within a portion of said casing interior and circuit breaker mechanism operative to suddenly open the controlled circuit at said contacts upon the occurrence of current overload, whereby arcing occurs within the said casing portion at said contacts, the provision of means for sealing the end cap means with respect to the arc flame and evolved gases, said casing portion including an end wall with a diametral split and longitudinal splits on opposite sides of the casing portion and said end cap means including an end cap with a side flange completely embracing said casing portion and with an end wall covering said casing end wall, said sealing means including a portion covering said longitudinal casing splits, said sealing means being held enclosed upon the said casing portion by said end cap.
2. An electric circuit breaker as claimed in claim 1, said sealing means comprising an end

75

portion mounted upon the outside surface of said casing end wall and covering the diametral split in said end wall and finger portions extending from the outer periphery of said disc portions at diametrically opposite portions thereof, said finger portions closing the portions of the longitudinal casing splits included within said end cap flange.

3. An electric circuit breaker as claimed in claim 1, said sealing means comprising an end portion mounted upon the outside surface of said casing end wall and covering the diametral split in said end wall and finger portions extending from the outer periphery of said disc portions at diametrically opposite portions thereof, said finger portions closing the portions of the longitudinal casing splits included within said end cap flange, said finger portions being deformed into sealing engagement over said longitudinal casing splits by the application of said end cap to the said casing.

4. In an electric circuit breaker having a hollow casing formed by separate casing sections held assembled together by exteriorly applied end cap means and including fixed and movable electrical contacts enclosed within a portion of said casing interior and circuit breaker mechanism connected with the movable contacts to cause these contacts to move automatically and rapidly to open position upon the occurrence of current overload with the occurrence of arcing within said casing portion, said circuit breaker means including a re-set actuator plunger extending through an opening in one of the casing end walls and projectable through said opening upon the occurrence of current overload, said casing end wall having a diametral split and said casing having opposed longitudinal splits extending along opposite sides of the casing, the provision of means for baffling the flow of the arc flame within said casing portion and for sealing the end cap means with respect to the arc flame and evolved gases, said means comprising baffle wall portions in said casing interior portion in adjacent relationship to conductor strips carrying said contacts and in position to shield said conductor strips from the direct action of the arcing flame, sealing means covering said casing splits on the outside of the casing, and sealing means on the plunger for sealing the said end wall opening on the inside of the casing when the said

plunger is projected through the opening upon the occurrence of current overload.

5. In an electric circuit breaker comprising a hollow cylindrical casing formed by separate casing sections forming the casing with a diametral split across one end wall thereof and longitudinal splits extending along opposite sides of the casing, and including fixed and movable contacts enclosed within a chamber portion of said casing which includes said casing splits, and circuit breaker mechanism connected to suddenly open the controlled circuit at said contacts upon the occurrence of current overload, whereby arcing occurs within said chamber portion at the contacts, said casing having an end cap retaining portion defined on its exterior surface and including an end cap firmly embracing the end portion of the casing which includes said chamber portion, said end cap having an end wall covering the said casing end wall and a side flange which completely embraces the portion of said casing containing said chamber portion and is held secured upon the outside of the casing by the engagement of the flange with said defined end cap retaining casing portion, the provision of means sealing said casing splits with respect to the interior of said chamber portion, said sealing means being confined upon the exterior of said casing by said end cap and including an end portion sealing said diametral casing split and side portions sealing said longitudinal casing splits.

6. In an electric circuit breaker including a split casing with fixed and movable contacts mounted within the casing and thermal means connected with the movable contacts so as to break the circuit at said contacts upon the occurrence of current overload or a short circuit, said casing having an exteriorly applied metal end cap holding the split casing together, the provision of insulating means over the casing splits and between the casing and said end cap, said insulating means preventing the end cap from forming an electrically conductive path with gases evolved within the casing upon arcing occurring when the current is suddenly interrupted at said contacts.
